WILBUR E. BARNES AND MELVIN E. BARNES, OF NEWARK, NEW JERSEY.

LOOM.

1,253,565.

Specification of Letters Patent. Patented Jan. 15, 1918.

Application filed February 8, 1916. Serial No. 76,969.

To all whom it may concern:

Be it known that we, WILBUR E. BARNES and MELVIN E. BARNES, citizens of the United States, and residents of Newark, 5 county of Essex, and State of New Jersey, have invented certain new and useful Improvements in Looms, of which the following is a specification.

This invention relates to an improved 10 loom, and is designed more particularly as a small loom operated by hand and adapted for home and school use for the weaving of scarfs, table runners, small rugs and similar articles, the loom being designed to be compact and to be simply operated.

The invention relates to a loom of this kind in which some of the warp threads are substantially fixed while other of the warp threads are adapted to be shifted above and 20 below the fixed warp threads so as to alternately form the shed above and below such fixed strand. Such fixed warp strands are preferably each alternate strand, and the mechanism for moving such movable warp 25 strands is a single heddle which is operated in one direction by a treadle, preferably a foot treadle, and in the other direction by a spring or springs disposed so as not to interfere with the operation of the loom but 30 still occupy a position that makes the movement of the heddle even and positive.

The invention further provides for a loom of this kind in which the heddle operating device, which permits its manual operation 35 such as the treadle, is so disposed as to give sufficient power to make the operation of the loom easy and to act as a stop for the upward movement of the heddle, which upward movement is caused by the springs aforesaid.

40 The invention further consists of details of construction which are fully set forth hereinafter and are finally embodied in the clauses of the claim.

In the drawing, Figure 1 is a top view, 45 broken away so as to condense the view, of our improved loom. Fig. 2 is a side view partly broken away to show the heddle operating means to better advantage. Fig. 3 is a front view of the loom shown in Figs. 50 1 and 2, and Figs. 4 and 5 are a section and broken end view, respectively, showing the means of attaching the warp threads to the beams.

The loom comprises two side structures 55 comprising the legs or uprights 10 arranged on each end of each side so as to form cor-

ner posts, these being connected on each side by longitudinally arranged side frames 11 which are preferably each made of one piece, although they can be made in a different 60 manner, the side frames 11 being attached to the legs 10 and acting to support the upper part of the loom mechanism, being suitably cut away at 12 to permit the passage of the shuttle into the shed. The side 65 frame on each side is raised as at 13 to give the proper amount of bearing for the heddle. The side frames act as bearings for the beams, the guide roll 14 and the breast-beam 15 acting to support the warp threads at a 70 proper height and being provided with suitable let-off and take-up beams 16 and 17, respectively, each of which latter can be provided with ratchets 18 and 19 respectively, and having the rectangular ends 20 75 and 21 for the reception of a suitably formed part 22 of the handle 23, this detachable handle being used for turning the let-off beam 16 and the take-up beam 17 when the weaver finds it necessary, and the ratchets 80 18 and 19 serving to hold the let-off and take-up beams against rotation when desired. The warp threads are arranged so that some of the threads are substantially fixed in position, for instance, each alternate 85 warp thread passes directly from the guide roll 14 to the breast-beam 15, as at 24. The remainder of the warp threads pass, as shown at 25, through the heddle frame 26, the heddle frame having the required number 90 of heddles 27 with the proper mails 28 which are attached to the laths 29 of the heddle frame. The side pieces 30 of the heddle frame slide in the grooves 31 in the side frames 11, the grooves 31 not extending 95 to the bottom of the side frames so that they form stops at their lower ends 32 to limit the downward movement of the heddle. The heddle frame is arranged so that its lower lath and upper lath stop on the re- 100 spective upward and downward movements of the heddle frame so as not to disturb what we will call in this specification, the fixed warp threads 24, so that when the heddle frame is thrown either upward or 105 downward it forms a shed either above or below the fixed warp threads 24, these sheds being illustrated at 33. To provide a smooth and easy operation of the heddle frame the strands 34 are attached near the outer ends 110 of the lower lath 29 of the heddle frame, or at any other suitable point near the sides

thereof, and are actuated by a proper operating device, in this form the operating device consisting of a joined treadle, the rear leaf 35 of which is hinged as at 36 to 5 the rear cross-piece 37, and it is also hinged as at 38 to the front leaf 39 which is held by the bracket 40 supported on the front cross-piece 41. The bracket simply supports the front end of the treadle and permits a slight 10 sliding movement of the front leaf 39. The strands 34 are fastened to the rear leaf 35 as near to the swinging end as desirable so as to give the heddle frame the proper amount of movement.

15 The rear leaf 35 and the front leaf 39 of the treadle are properly chamfered as at 42 so that when they are in their upward positions shown in full lines in Fig. 2 they act as a stop to limit the upward movement 20 of the heddle frame, the heddle frame being moved upward by springs when the foot treadle is released. These springs 43 are arranged on each side and are fastened at their bottom ends as at 44 to the rear 25 posts 10 on each side of the loom frame and are extended over a suitable supporting rod 45 which extends from one side to the other, the free ends 46 of the springs 43 being arranged to press against the lower 30 outer edges of the heddle frame so as to give a pressure on each side near the end of the heddle and thus equalize its movement and insure it against binding in the machine frame. The arrangement of the springs is 35 such as to provide a minimum of interference with the operation of the loom, the springs being installed so that they have a substantially long free end and the pressure does not materially increase as the 40 spring is flexed in lowering the heddle. This makes the loom easy to use.

The reed frame consists of two side strips 47 which are hinged at 48 to the longitudinal braces 49 and can be swung forward and 45 backward. The upper part of the heddle frame is provided with suitable heddles 50 through which the warp strands pass, as is usual in looms. The warp threads are fastened to the take-up beams by securing a 50 strip of canvas or the like, as 51, to the beams, one of which, 17, is shown in Figs. 4 and 5. The canvas strip may be attached by suitable tacks or nails 52 and may have suitable gromets or eyelets 53, and the warp

threads are knotted as at 54 into these 55 gromets and thus held against being released, as will be evident.

On the operation of the loom the parts are normally in the position shown in the drawing, forming the upper shed 33, and 60 the weft is passed through the shed in any desired manner either by a shuttle or other means, and then the treadle 39 is pressed. This pulls the heddle frame down, overcoming the pressure of the spring 46, and a 65 lower shed is formed, that is a shed beneath the fixed warp threads 24, and the weft is again passed through usually in the opposite direction from the first-mentioned passage, and then when the pressure is removed 70 from the treadle the original position is assumed and by a repetition of these movements and the formation of the alternate sheds the weft threads are inserted. When necessary, the filling is pressed into place 75 by means of the beater or reed frame 47 which, when pulled forward, causes the reeds 50 to engage the weft threads and force them into compact relation in the product of the loom. 80

Having thus described our invention, we claim:

A loom comprising side frames with grooves therein, a heddle frame sliding in the grooves, a treadle consisting of a rear 85 leaf hinged to the frame of the loom, a front leaf hinged to the rear leaf and having a loose connection with the frame of the loom, said connection acting as a fulcrum and permitting a sliding movement 90 of said front leaf, strands connecting the heddle frame and the rear leaf of the treadle, the front and rear leaves of the treadle being chamfered at an angle so that when they abut they limit their upward 95 movement and therefore limit the upward movement of the heddle frame, the bottom of the grooves in the frame being placed so as to limit the downward movement of the heddle frame, and yielding means for 100 forcing the heddle frame to its normal position.

In testimony that we claim the foregoing, we hereto set our hands, this 5th day of February, 1916.
